UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed May 13, 1922. Serial No. 560,662.

To all whom it may concern:

Be it known that I, CHARLES GILBERT HAWLEY, a citizen of the United States, and a resident of Chicago, Cook County, Illinois, have invented certain new and useful Improvements in and for Locomotive Boilers, of which the following is a specification.

My invention relates to internally-fired boilers and more particularly to locomotive boilers and its object is to increase the capacity, efficiency and durability of such boilers. To this end, I apply water-circulating-and-steaming attachments to and within the firebox of the boiler, thereby adding greatly to the heating surfaces of the firebox and bringing about a rapid circulation of the water throughout the boiler, whereby all of the heating surfaces of the boiler are increased in efficiency.

The particular object of the invention is to provide water-circulating elements or attachments which may be readily placed in fireboxes of ordinary design, and which, in themselves shall be of simple and inexpensive form.

My invention will be readily understood on reference to the accompanying drawings, in which Fig. 1 is a vertical longitudinal section of a locomotive firebox embodying my invention; Fig. 2 is a cross section thereof; Fig. 3 is like unto Fig. 1, but illustrates a water-heating-and-circulating attachment of a more restricted form; Fig. 4 is a cross section taken from Fig. 3; Fig. 5 is a plan view taken from Fig. 3; Figs. 6, 7, 8 and 9 are detailed views of one of the attachments, the better to disclose the construction thereof.

I have herein shown locomotive fireboxes of both plain (Fig. 3) and combustion chamber (Fig. 1) types. The parts 2 and 3 will be recognized as respectively the crown sheet and the throat sheet of the firebox. Briefly, I provide the throat sheet with a horizontal slot or opening 4 and the crown sheet with a longitudinal slot or opening 5. By preference two pairs of openings are formed in the sheet, as represented in Figs. 2, 4 and 5. For each pair of openings, which obviously are at right angles to one another, I provide a water-steaming-and-circulating element in the form of a hollow stay-bolted water wall. The water walls of Figs. 1 and 2 are marked A. Those of Figs. 3, 4 and 5 are marked B.

They differ only in shape, the wall A being the wider at the top and presenting a longer outlet opening or slot 5 in the crown sheet. Each of these members or hollow walls comprises two sheets of metal preferably of the same kind and thickness as the crown and side sheets of the firebox. These two sheets are warped or twisted (by any suitable means) into substantially the shapes herein depicted. Their edges are then flanged together as well shown in Figs. 7 and 9. The flanged edges are united by welds 6, leaving only the upper and lower ends of the wall open. The spaced-apart sheets are joined by closely spaced stay-bolts 7, as they must withstand the internal pressure of the boiler. By preference the upper and lower ends of each member are flanged outward as shown in Fig. 9 in order that they may be welded to respective sheets 2 and 3. By preference the flanges 8 are made wide enough to receive certain of the stay-bolts 9 and 10, so that the member may be spoken of as finding support from the shell of the boiler.

The heating surface thus added to the firebox is of the utmost importance and as will be obvious the rapid heating and evaporation of water within these members brings about a vigorous fore-and-aft circulation of water in the boiler. An important result consists in the constant flooding of the crown sheet of the firebox with water from these tortuous or contorted water walls. The flooding of the crown sheet insures the safety thereof in the event of low water in the boiler.

The oppositely or reversely disposed members or walls of each firebox serve as in the nature of a fire arch therein, and, as illustrated in Fig. 4, they may be supplemented by a number of arch brick 12. These brick are conveniently supported by the water-circulating members. Furthermore, the oppositely disposed contorted walls admirably serve the purpose of directing the firebox flames energetically against the side and crown sheets of the firebox.

A distinct purpose in this invention and attained hereby resides in the flexibility of the twisted or contorted members through which they are enabled to absorb all expansion and contraction stresses which might tend to disrupt the same or the connections thereof to the crown and throat sheets.

Having thus described my invention, I claim as new and desire to secure by Letters Patent:

1. A locomotive boiler and its contained firebox in combination with a pair of hollow stay-bolted water walls applied to the firebox, said walls being oppositely twisted and each thereof presenting a horizontally elongated intake opening at the front leg of the firebox and a like outlet opening longitudinally elongated in the crown sheet of the firebox.
2. A locomotive boiler and its contained firebox in combination with a pair of hollow stay-bolted water walls applied to the firebox, said walls being oppositely twisted and each thereof presenting a horizontally elongated intake opening at the front leg of the firebox and a like outlet opening longitudinally elongated in the crown sheet of the firebox.
3. A locomotive boiler and its contained firebox in combination with a pair of hollow stay-bolted water walls applied to the firebox, said walls being oppositely twisted and each thereof presenting a horizontally elongated intake opening at the front leg of the firebox and a like outlet opening longitudinally elongated in the crown sheet of the firebox, the lower portions of said walls constituting a partial fire arch in the lower front part of the firebox.
